UNITED STATES PATENT OFFICE.

DAN RYLANDS, OF BARNSLEY, COUNTY OF YORK, ENGLAND

MACHINERY FOR THE MANUFACTURE OF BOTTLES.

SPECIFICATION forming part of Letters Patent No. 416,376, dated December 3, 1889.

Application filed January 23, 1889. Serial No. 297,326. (No model.) Patented in England March 3, 1888, No. 3,263.

To all whom it may concern:

Be it known that I, DAN RYLANDS, a subject of the Queen of Great Britain, residing at Barnsley, in the county of York, England, have invented new and useful Improvements in Machinery for the Manufacture of Bottles, (for which I have obtained a patent in Great Britain, No. 3,263, bearing date March 3, 1888,) of which the following is a specification.

My invention relates to improvements in machinery for making bottles, jars, or other hollow ware in glass.

In order to make my invention more clearly understood, I have annexed hereto six sheets of drawings, to which the following description relates, and in which the same figures of reference indicate the same parts.

Figures 1 and 2 are elevations; Fig. 3, a plan view. Figs. 4, 5, and 6 are elevations, partly in section, showing one complete mold and apparatus for operating the same. Figs. 7, 8, and 9 are plan views of molds and mold-operating apparatus; Fig. 10, a sectional elevation of blow-pipe-admission valve, and Fig. 11 an elevation of same.

Referring to Fig. 1, 1 is a pillar supporting bracket 2, at the outer end of which is formed a tubular guide 3, for the reception of the sliding ram 4; 5, a lever fulcrumed at 6 and connected to ram 4 by link 7; 8, a balance-weight; 9, a tapered pin or plunger secured to and carried by ram 4; 10, a table capable of intermittent rotary movement around the central pillar 1.

11 11 are bottle-molds carried by studs 12 12.

The method of opening and closing the different portions constituting the complete mold is shown more fully in Figs. 4, 5, 6, 7, 8, and 9.

13 13 are detents capable of dropping into recesses formed in sector 14.

15 15 are handles operating detents 13 13 through shafts 16 16.

17 18 are circular paths formed in the framing 19, the angular outer pathway 17 being formed with a double incline or depression extending from 20 to 21, the remaining portion of the pathway being level. (See Figs. 1 and 2.) The inner pathway 18 has also a rising and falling incline, rising from 22 to

23, Fig. 3, level from 23 to 24, and descending to the level of the otherwise level pathway at 25.

Figs. 4, 5, 6, 7, 8, and 9 show one mold and the apparatus for operating same.

26 26 26 are stationary cams secured to central pillar 1.

27 27 27 27 are plungers having bearings 60 in guide 28.

29 29 29 29 are bowls or runners carried by plungers 27; 60, spiral springs carried by the plungers 27, one of which is shown by Fig. 9. 30 30 are connecting-links between the different sections of mold and plungers 27 27.

The molds shown are arranged to make imperial half-pint bottles, and open at top and bottom, and are built up in sections, each section being hinged and capable of opening, as shown in plan views 7, 8, and 9. The bottom section 31 has an internal diameter equal to the external diameter of the bottle to be made, and constitutes the body portion.

32 is one of the neck-molds of smaller diameter than the intended neck.

33 is the portion forming the mouth of the bottle; 34, a neck-mold having its internal contour formed to produce a neck of the desired form, as shown at 35, Fig. 6; 36, a sliding annular ram forming a portion of the bottle-bottom and actuated through runner 37 by pathway 18; 38, a solid ram finding a bearing in interior of annular ram 36 and having movement given to it by runner 39 and pathway 17.

It will be observed that the upper surfaces of the two rams, as shown by Fig. 6, will produce the formation of bottle-bottom required.

Fig. 4 is an elevation, partly in section, on line 23, (see Fig. 3,) Fig. 7 being a plan view of same, and shows mold and actuating apparatus in the charging position, the annular ram 36 being at its highest and solid ram 38 at its lowest position, the bottom section of mold 31 being closed and the neck and mouth portions 32, 33, and 34 being open, as shown.

Fig. 5 shows the position assumed by the various parts on line 24, (see Fig. 3,) which represents the plunging or pressing position, the annular and solid rams being at their highest position, the sections of molds 32 33 being closed and neck portion 34 open.

Fig. 6, taken on line 25, Fig. 3, shows the

blowing position, the annular plunger 36 having now reached its lowest position, the smaller neck-mould 32 having opened and the neck-mold 34 closed.

5 Fig. 10 is a sectional elevation of blow-pipe-admission valve, in which 40 is the valve, 41 the valve-casing, and 42 an attachment for opening the valve, the spring 43 serving to close the valve. 44 is a sliding bracket working in guides fixed to bracket 2, (see Figs. 1, 10 2 and 3,) and to this bracket the blow-pipe valve is attached.

Having now explained the various parts appertaining to my invention, I proceed to show 15 the method adapted in producing, say, an imperial half-pint bottle.

Referring to Figs. 4 and 7, which show a mold in the charging position, the bottom portion of the mold 31 being closed, the neck 32 20 34 and mouth portions 33 open, the annular ram 36 being at its highest and solid ram 38 at its lowest position, it will be seen that the molten metal is charged into and contained 25 by the space surrounded by the annular and solid rams. The table 10 and the charged mold being now rotated into position under the pressing plunger or pin 9 on line 24, Fig. 13, will result in the neck 32 and mouth 33, portions of the mold closing by 30 reason of fixed cams 26, plungers 27, bowls 29, links 39, and assuming the position shown by Figs. 5 and 8. The internal solid ram 38 in the meantime by means of inclined annular pathway 17 and runner 39, reaches its 35 highest position and determines the length of the finished bottle. The pressing plunger or pin 9, being now operated by lever 5, will result in the molten metal being pressed into the form indicated. The plunger 9 being 40 withdrawn and the table 10 again rotated, will cause the opening of the neck-mold 32 and the closing of the neck-mold 34, intended to produce the formation of neck usual in a 45 half-pint bottle. The annular ram 36, by pathway 18 and runner 37, will now have fallen to near the bottom of the body-mold 31 and level with the upper surface of the solid ram 38, the two rams conjointly forming 50 the bottom of the intended bottle and being so shaped as to produce the formation required. The mold containing the pressed bottle will now have arrived at the blowing position indicated by dotted line 25. (See Fig. 3.) The pressing-lever 5 being again operated, will cause the sliding bracket 44 and attached blow-valve to descend till the projecting nipple on the blow-valve casing will have entered the mouth of the bottle, the attachment 42, Fig. 11, in the meantime having 55 come in contact with the upper surface of the mouth-mold 33, raising the valve 40, when blowing will commence and will continue till the pressing-lever is again lifted. The attachment being now free from the upper surface 60 of the mouth-mold, the spring 43 is free to 65 close the valve.

In Fig. 3 on line 23 the various sections of one mold are shown in the position they occupy during the charging position; (see Fig. 4,) the space surrounded by interior of annular ram 36 being sufficient to contain without overflowing the quantity of molten metal requisite to form the finished bottle. The molten metal is charged into the molds as they alternately arrive into the charging position by means of a ladle, or metal can be gathered on an ordinary blow-pipe and allowed to flow from the pipe into the mold. Any desired form of bottle or jar can be produced.

Having thus fully described my invention, what I claim, and desire to secure by Letters Patent, is—

1. In a bottle-making apparatus, the table 10, capable of intermittent rotary movement 85 and carrying the sectional mold 11 successively into the charging, pressing, and blowing positions, in the manner and for the purposes described.

2. The sectional bottle-mold 11, the separate sections of which are capable of being closed and opened by fixed mechanical devices, as described, or their equivalents, and having bottom of such mold supplied by the upper surfaces of the annular and solid rams 95 36 38.

3. The circular pathways 17 18, having rising and falling inclines and actuating the annular and solid rams 36 38, in manner described.

4. The bottle-mold 11, capable of receiving through the bottom thereof the annular and solid rams 36 38, the dimensions of such mold and of such annular and solid rams, respectively, being such that when the annular ram 36 is at its highest position and the solid ram 38 at its lowest position the space in the interior of such mold shall be sufficient to contain, without overflowing, the exact quantity of molten glass required to form a finished bottle of the required size, thereby affording a measure by which uniformity in the weight of the finished bottles can be obtained by mechanical means.

5. The blow-pipe-admission valve 40, with fixed devices, as described, or their mechanical equivalents, for operating the blow-pipe and automatically opening the valve when the bottle-mold 11, carried by rotating table 10, arrives at the blowing position, and for closing same when the blowing is completed and the rotating table carries such mold away from such blowing position.

6. The blowing arrangements, as described, consisting of blow-pipe, blow-valve 40, valve-casing 41, attachment 42, and sliding bracket 44.

7. The combination, with a bottle-mold, of the annular ram 36 and the solid ram 38, working through the bottom of the bottle-mold, and operating as described.

8. The combination, with a bottle-mold, of

the rams 36 38, the circular pathways 17 18, and runners 39 37, as and for the purposes described.

9. The combination, with a bottle-mold, of 5 the rams 36 38, pathways 17 18, and rotating table 10.

10. The combination, with a bottle-mold, of the rotating table 10, the blow-valve 40, attachment 42, and sliding bracket 44.

11. The combination, with a bottle-mold, of 10 the pressing-plunger 9, carried by ram 4, and the rotating table 10.

12. The combination of the bottle-mold 11, composed of two or more sections, with

mechanical devices, as described, or their 15 equivalents, for closing and opening the same successively, rotating table 10, rams 36 38, and plunger 9.

13. The combination, with the bottle-mold, 11, of the rotating table 10, pressing-plunger 20 9, ram 4, lever 5, and rams 36 38.

14. The combination, with the bottle-mold 11, of the table 10, rams 36 38, pathways 17 18, plunger 9, and blow-valve 40.
